UNITED STATES PATENT OFFICE.

RICHARD CHARLES RATTO, OF WATERBURY, CONNECTICUT, ASSIGNOR TO THE PLUME & ATWOOD MANUFACTURING COMPANY, OF WATERBURY, CONNECTICUT, A CORPORATION OF CONNECTICUT.

ELECTRIC-LIGHT FIXTURE.

1,091,961.

Specification of Letters Patent. Patented Mar. 31, 1914.

Application filed August 31, 1913. Serial No. 785,950.

To all whom it may concern:

Be it known that I, RICHARD CHARLES RATTO, a citizen of the United States, residing at Waterbury, in the county of New Haven and State of Connecticut, have invented a new and useful Improvement in Electric-Light Fixtures, of which the following is a specification.

This invention relates generally to electric light fixtures and more particularly to that class of fixtures in which there is a central body portion from which radiate arms to which the incandescent light is connected either in a pendent or upright position.

The object of my invention is to provide a fixture embodying either round or oblong shaped arms and frames and which shall be of such construction that considerable time can be saved in wiring the fixture, and another object is to provide a fixture of such construction that the wiring of the arms can be accomplished from the socket end with great ease, and the danger of stripping the covering from the wire is completely eliminated.

Heretofore in constructing fixtures of this general class it has been customary to attach the socket to a solid end body carried at the outer ends of the arms and in this construction it was usual to employ what is known as an electric center body in connection with a hickey and the wires have been drawn down through the central pipe and out through the radiating arms through the solid end bodies which have been bored at right angles and in so wiring the fixture there was always danger of stripping the covering from the wire.

By my novel construction of fixture I am able to use the ordinary gas center body in connection with an ordinary insulating joint and completely avoid the use of the hickey and consequently eliminate the cost of these parts as well as save considerable time in the wiring operation. Furthermore the lamp carrying arms are held firmly against twisting and the weight of the article as a whole is considerably reduced.

Another object of my invention is to provide a novel method of attaching the nipples to end bodies and also provide differential seating rings whereby different sizes of round tubular arms can be employed.

With these various objects in view, and with certain others as will appear herein-

after my invention consists in the novel features of construction, combination and arrangement all of which will be fully described hereinafter and pointed out in the claims.

In the drawings forming a part of this specification: Figure 1 is a side view partly in section showing the central portion and one arm of the fixture embodying the round arm and end body. Fig. 2 is a top plan view of the same. Fig. 3 is a longitudinal sectional view. Fig. 4 is a detail perspective view showing the various parts detached. Fig. 5 is a side view showing the square or tubular shaped arm. Fig. 6 is a plan view of the same. Fig. 7 is a vertical longitudinal section. Fig. 8 is a detail perspective view of the parts detached.

In carrying out my invention I employ a central frame A which may be circular in form as shown in Figs. 1 and 2 or square as shown in Figs. 5 and 6 and centrally located in this frame A is the union B to which the supporting pipe is connected and from which radiate the pipes or rods C, said pipes or rods being threaded into the union at their inner ends as shown and having their outer ends threaded as indicated at C'. It will of course be understood that there are openings produced in the frame through which the pipes or rods C emerge and upon the exterior of the frame surrounding said openings are the seating rings D securely fastened to the frame and then suitably mounted. It will of course be understood that this seating ring D is circular in form in the round arm fixture and square in the square arm fixture. And if desired the square seating ring or ferrule of the square arm can be permanently attached to the inner end of the said arm and fitted into the square opening in the frame.

E indicates the lamp carrying arm which as before stated can be circular in cross section as shown in Figs. 1, 2, 3 and 4, or square or oblong in cross section as shown in Figs. 5, 6, 7 and 8, this arm E enveloping the outwardly extending pipe or rod C as most clearly shown.

In the construction shown in Figs. 1, 2, 3 and 4 the outer end of the arm E bears against a seating ring F circular in form and provided with oppositely disposed flanges F', one of which extends into the arm E while the other enters a circular opening in

the end body or shell G, said end body or shell G having a nipple H attached thereto and to which the light socket is connected. This nipple H has its end inserted in the shell G and is then rolled over as shown at H' before being cemented and in this manner is securely connected to the shell so that all possibility of the nipple working loose is avoided. The shell or end body G has an opening G' opposite to that in which the ring F seats, said opening G' being preferably smaller than the other opening and the threaded end C' of the pipe or arm C approaches this opening G' when the various parts of the fixture are properly assembled and in order to securely bind them together I employ a nut I which screws upon the end C' and seats in the opening G', and when this nut is properly screwed upon the threaded end of the pipe or rod the arm, seating ring and end body or shell will be securely and firmly connected to the central frame A.

It will be noted that the shell or end body G is hollow and that ample space is provided through the seating ring and arm for the passage of the wires up through the central portion of the frame and consequently the fixture can be wired from the socket end and all danger of stripping the covering from the wire is avoided and furthermore the parts can be so firmly connected that all danger of the socket being misplaced is completely avoided.

In practice I prefer to make the flanges F' of the seating ring F of different diameters so that the said ring can be used in connection with different sizes of arms and end bodies. In Figs. 5, 6, 7 and 8 the arms E are square in cross section and the end bodies or shells K are cubical in form having an opening K' at the inner side surrounded by integral lips K² while at the opposite side is the opening K³ in which screws the nut I for the purpose of connecting these parts together as previously described. The lips K² fit into the end of the arm E as shown in Fig. 7 and consequently hold the shell or end body in proper fixed position. The nipple H is connected to the cubical shell or end body in exactly the same manner as the round or globular shell. It will be noted that the same space for wiring from the socket end is provided in this construction as in the construction shown in Figs. 1, 2 and 3 and the same rigidity of the fixture as a whole is obtained in this construction as in the other.

It will thus be seen that I provide a fixture which can be quickly and easily put together and taken apart, one in which I eliminate several accessories usually employed in fixtures of this type and one which will ef-

fect a saving both in the manufacture of the article itself and in the labor employed in the installation of the fixture. It will thus be seen that I provide a novel construction of fixture capable of carrying out all of the objects hereinbefore referred to.

What I claim is:—

1. A device of the kind described, comprising a hollow end body to which a socket is adapted to be attached, said hollow end body having oppositely disposed openings, a central frame, an arm extending from said central frame and connected with the hollow end body, and a rod extending from the center of the central frame through the arm and through the hollow end body, and a nut adapted to screw upon the outer end of said rod and close one of the openings in the hollow end body.

2. A device of the kind described comprising a hollow end body having a nipple connected thereto and provided with oppositely disposed openings, a central frame, a hollow arm extending from the central frame to the hollow end body, a seating ring adapted to receive the end of said arm, a rod extending from the center of the central frame through the hollow arm and also the hollow end body, and a nut adapted to screw upon the threaded end of said rod and bind the parts together and close the outer opening of the hollow end body.

3. A device of the kind described comprising a hollow end body having a nipple connected thereto provided with oppositely disposed openings, a nut adapted to fit in one of said openings, a seating ring adapted to fit in the opposite opening, a hollow arm adapted to bear against said seating ring, a central frame to which the opposite end of said hollow arm is connected and a rod extending from the center of the central frame through the hollow arm, seating ring and hollow end body, the end of said rod being threaded and engaging the nut for the purpose specified.

4. A device of the kind described comprising a frame having a central union, a rod extending from said union radially through the said frame, a hollow arm arranged upon the exterior of the frame and surrounding said arm, a hollow end body having oppositely disposed openings, a nut adapted to engage the threaded end of the rod and close the outer opening of said hollow end body, and means connected with the hollow end body and central frame for positioning the hollow arm, as set forth.

RICHARD CHARLES RATTO.
